UNITED STATES PATENT OFFICE.

JAMES B. TOPHAM, OF ZELIENOPLE, PENNSYLVANIA.

DESIGN FOR A TIRE.

Application filed December 12, 1921. Serial No. 521,952. Term of patent 3½ years.

To all whom it may concern:

Be it known that I, JAMES B. TOPHAM, a citizen of the United States, residing at Zelienople, in the county of Butler and State of Pennsylvania, have invented a new, original, and ornamental Design for a Tire, as shown in the accompanying drawing and described in the following specification.

In the drawings

Figure 1 is a plan view of a portion of an automobile tire illustrating my new design, and

Figure 2 is a transverse sectional view of

the same.

I claim:

The ornamental design for a tire, as shown.

JAMES B. TOPHAM.

Witnesses:

JOHN E. KOCHER,
PEARL McCORMICK.
